UNITED STATES PATENT OFFICE.

ARTHUR S. FERGUSON, OF SPRINGFIELD, MISSOURI.

MUTOSCOPE.

948,272.

Specification of Letters Patent.

Patented Feb. 1, 1910.

Application filed December 26, 1908. Serial No. 469,512.

To all whom it may concern:

Be it known that I, ARTHUR S. FERGUSON, a citizen of the United States, residing in the city of Springfield, county of Greene, 5 State of Missouri, have invented an Improvement in Mutoscopes, of which the following is a specification.

My invention is an improvement in that class of mutoscopes which are adapted for 10 use as a toy or parlor amusement, the same consisting essentially of a series of photos or other pictures arranged radially in a circle thus forming what may be termed a picture-wheel, which being rotated, the 15 pictures are successively turned back and thus exhibited to the onlooker.

It will be understood that the photos or other pictures show successive changes of position of a body in motion, as for example 20 a dancer.

The invention is embodied in the manner of attaching the pictures together and to a flexible holder thus forming what may be termed a pad or pack of pictures adapted to 25 be secured around a rotating axle and thus form the picture wheel above referred to.

The invention further includes the case or housing in which the picture wheel is mounted and certain novel features of construction and combination of parts constitute such casing.

In the drawings Figure 1 is a vertical section of the complete machine, the hinged cover of the casing being shown by dotted 35 lines as thrown back on its pivot. Fig. 2 is a perspective view of a pack of photos or other pictures. Fig. 3 is a perspective view of the axle of the machine together with other parts attached thereto. Fig. 4 is a 40 horizontal section of the machine. Fig. 5 is a view illustrating the attachment of the picture pads or packs to the axle. Fig. 6 is a section on the line 6-6 of Fig. 5, of the picture wheel proper, the pictures being 45 thrown back on one side by pressure applied manually. Fig. 7 is a transverse section of a portion of a pad or pack of pictures. Fig. 8 is a cross section on the line 50 8-8 of Fig. 5. Fig. 9 is a perspective view 55 of a pad or pack of pictures. Fig. 10 is a perspective view supplemental to Fig. 9. Fig. 11 is a perspective view of the bottom portion of the pack of pictures.

Referring in the first instance to Figs. 1 55 and 4, A indicates the casing or sheet-metal box inclosing the picture-wheel B. The cas-

ing is provided with a hinged cover a which may be thrown back on its pivot a', as shown in Fig. 1, when it is desired to obtain access to the wheel B for any purpose, say for removing it and for insertion of another. The said wheel is formed of a series of photos or other pictures, arranged radially around its axis C, whose ends are supported in notched ears a² forming attachments of the 60 inner side of the casing A. Thus the wheel is adapted to be readily inserted in, or removed from, the casing. The axle is provided at one end with a large spur gear D, as shown in several figures, and thus meshes 65 with a pinion or small gear E, which, as shown in Fig. 4, is mounted on a short crank-axle that is journaled in the side of the casing and provided exteriorly of the latter with a crank F. It is obvious that by 70 rotating the said crank, the axle, together with the picture-wheel proper fixed thereon, will be rotated, and in such case the pictures come successively in contact with a trip G consisting of a metal strip, or finger, which is pendent from the front end of the hinged casing section a, as shown in Fig. 1. The pictures being successively thrown back are exposed to view through the glass plate a³, 75 Fig. 1, forming an attachment of the casing A, and the motion of the wheel is sufficiently rapid to produce the same impression as moving pictures as exhibited by larger machines and thrown upon the screen for the 80 amusement of large audiences.

The manner of securing together the required number of photos or other pictures to constitute the picture-wheel proper, and the manner of securing them to and around the axle C, is as follows: The required number of photos or other pictures is put together so as to form a rectangular pack, as shown in Fig. 2, and two parallel grooves b are sawed, or otherwise cut, in the base end of the pack. A hole b' is also formed through the pack at a point midway between the grooves b, b. The latter are for the purpose of receiving cords b² shown in Figs. 5 and 9, whose ends are carried up and secured to the outer side of a piece of stiff cardboard H. The hole b' is for receiving an elastic cord b³, whose ends are arranged and secured in the same way as the inelastic cords b². A pad, or rectangular piece, of leather b⁴, as shown in Figs. 7 and 10, is laid over the end of the pack in which the grooves b are cut, and the ends of the same extend 90 95 100 105 110

up on the sides of the pack as shown in said figures. The leather piece b^4 is glued to the base of the picture pack, and also upon the cardboard H and thus over and upon the ends of the cords b^2, b^3 .

It will be seen that the cords b^2 tie together the base ends of the pictures composing the pack B and that the leather piece b^4 serves the same purpose, and, in addition, 10 it aids in holding the ends of the cords secured tightly to the cardboards H which are arranged at the ends of a pack. Such leather together with the several cords b^2, b^3 , is glued or otherwise firmly secured in place, 15 and thus the cords are held firmly and also the ends of the pictures forming the pack B .

The means for securing a pack of pictures B to the axle C and thus forming a picture-wheel as represented in several figures, is as follows: A sheet metal clip I is secured to the cardboards H at one end of the pack. The same consists of a metal strip extending across the end of the pack and having its ends inturned to form catches as 20 indicated at i . As shown in Fig. 3, the axle C has a radial longitudinal flange c , and over this flange the end portions i of the clips I are adapted to slide, as will be understood by reference to Fig. 10. The 25 clip I at one end of the pack B having been thus applied to the flange c , the pack is bent around the axle, the leather piece b^4 thus coming into contact with it, as will be understood by reference to Fig. 6. The two card- 30 board strips are thus brought together, as indicated in Fig. 6, and are further secured to the axle flange c by any suitable means. I have devised various means for this purpose, but I show an eye bolt h , Figs. 6, 7, 8, 40 which has a long shank, the same being passed through the coincident openings in the cardboards H , and the axle flange c , which is provided with a hole c' and the cardboards H with openings h' for this purpose. 45 When the cardboards H have been thus brought together on opposite sides of the axle flange c , a hook h^2 , see Figs. 5 and 6, is engaged with the eye h . In this manner the picture pack proper B is applied to the 50 axle C and secured detachably thereto. The picture-wheel proper being thus completed,

and it being placed in the casing A , as shown in Figs. 1 and 4, the machine is ready for operation, as before indicated.

The elasticity of the cord b^3 and its location a little above the base of the picture pack B , adapts it to perform a very useful function, which is to increase the resiliency of the pictures, or cause them to more quickly resume their normal position after being turned back as indicated in Fig. 1. In other words, the normal spring or elasticity of the pictures is increased by the location and function of the cord b^3 .

I claim:

1. In a picture-exhibitor of the type indicated, a picture-wheel comprising an axle having a radial flange, a picture pack formed of a series of pictures which are flexibly connected at the base, pieces of flat rigid material attached to the ends of the pack adjacent to the base, and means for securing them in parallel position when the pack is applied around said axle, substantially as described.

2. In a picture wheel, the combination with an axle having a radial flange, of a pack of pictures secured together flexibly at the base, and provided with devices for engaging the said flange, and means for securing the ends of the pack together, and to the axle flange, substantially as described.

3. In a picture exhibitor, the combination with a picture pack having an opening near the base which extends through the same and an elastic cord arranged in such opening and its ends secured upon the ends of the pack, as and for the purpose specified.

4. The improved picture-wheel comprising a rotatable axle having a radial flange, a picture pack having a flexible base, and means for securing it to said flange, and an elastic cord passing through the pack at a point slightly removed from the base, as and for the purpose specified.

In testimony whereof I have signed my name to this specification in the presence of two subscribing witnesses.

ARTHUR S. FERGUSON.
